UNITED STATES PATENT OFFICE.

RICHARD A. MAGILL, OF ATLANTA, GEORGIA.

GUIDE FOR RULING-MACHINES.

984,281.

Specification of Letters Patent. Patented Feb. 14, 1911.

Application filed June 3, 1908. Serial No. 436,353.

To all whom it may concern:

Be it known that I, RICHARD A. MAGILL, a citizen of the United States, residing at Atlanta, in the county of Fulton and State 5 of Georgia, have invented certain new and useful Improvements in Guides for Ruling-Machines, of which the following is a specification.

This invention relates to ruling machines, 10 more particularly to the guide cords therefor, and has for its essential purpose, to devise a means whereby a single continuous cord may be utilized in place of the large number of guiding cords now used on all 15 ruling machines.

Another object is to obviate the disadvantages attending the use of a plurality of cords whereby it is necessary that each individual cord be adjusted, thus saving considerable time when preparing the machine 20 for ruling.

A further purpose is to perfect a guiding means for the sheets of paper so that said sheets, uniformly and evenly, may be delivered 25 to the inking pens.

Another advantage is that the use of a single thread requires only one knot, as against a separate knot for each individual cord thereby reducing to a minimum the 30 possibility of breakage, thus increasing the life of the same and saving the time necessary for repairing broken threads. The single knot likewise eliminates the interference of many knots with the ruling pens 35 and so gives an unbroken line.

The apparatus is of such design that it may be readily attached to the frame of the ordinary ruling machine.

With these and other subordinate objects 40 in view, my invention is further set forth in the following specification and appended claim and illustrated in detail in the accompanying drawings, wherein:—

Figure 1 is a side elevation of a ruling 45 machine with my improved guiding means thereon. Fig. 2 is a side elevation of the upper guiding cords. Fig. 3 is an end elevation of the same. Fig. 4 is a side elevation of the guiding means at the opposite 50 end of the machine. Fig. 5 is a plan view of a section of Fig. 4, and, Fig. 6 is a rear end elevation of Fig. 4.

Referring now more in detail, to the several views shown, wherein like letters of reference indicate the same parts in the different figures shown, the character *t* designates

the usual conveyer belt or apron on the ruling machine frame *a* and *X* one of the running pulleys therefor. Said belt coöperates with the guiding element *b* to receive the 60 blank sheets of paper as they are fed from the shelf *c'* and carry said sheets forward to the ruling pens after the known manner. *c, c'*, represent two detachable brackets secured to the posts *b* at one end of the frame *a*, said brackets are provided with trunnions at their upper ends for the shaft of the grooved roller or pulley *j*, and *d* designates a larger grooved pulley which is mounted within journal blocks *d'* upon the frame of 65 the machine. The pulley *d* is the driving member for which purpose it is provided with an operating crank *e*. Within the sides of the frame posts *b* are located two compensating or directing guide pulleys *h, h'*, 70 whose purpose will be presently described.

Secured upon the frame at a suitable distance from the end supporting brackets and in alinement therewith, is a secondary bracket *c'*, removably secured to the frame, 80 having journaled therein the ordinary upper and lower guiding pulleys *g'* and *g* respectively. The lower guiding pulley *g* is provided with tensioning means *h* whereby the tension of the several convolutions or 85 guiding elements of the cord may be regulated. Intermediate the primary and secondary brackets *c* and *c'* respectively is the guiding bar *a'* fixed transversely of the frame. Thus the course of the upper guid- 90 ing means of the machine is the following; the thread *f* runs from the grooved roller *j* in the direction of the arrow through the pulley *h'*, thence transverse of the machine through the second directing pulley *h*, 95 thence around the driving roller *d*, across the stationary bar *a'*, around the adjusting roller *g*, around the roller *g'* and again to the roller *j*. It will therefore be readily seen that the convolutions of the thread *f* 100 are directed to the starting point of the roller *d*, by which means it is again started on its course around the several pulleys *j, d, g, and g'* respectively.

Referring now to the figures disclosing 105 the lower guiding means at the opposite end of the machine, *s* designates the main roller for the ruling cloth *t*, and *t'* is a roller for supporting said cloth on its return after passing over the roller *s*. *l* refers to the 110 endless guiding cord, comprising the plurality of separate guiding elements, corre-

sponding to those shown at *f* in Figs. 1, 2 and 3, and in its arrangement for operation these guiding elements are strung upon the rollers *q*, *s*, *r*, *r'*, and *m*, thence to *q* in the 5 order given, said pulleys *r'* and *m* are journaled in the end frame supports or posts *b'*. After having passed about these pulleys, the required number of times the cord is directed from the end of the pulley *m*, through 10 the guiding pulley *o*, (as shown in Fig. 6) then transverse of the machine through the pulley *p*, from which pulley *p* it passes on to the roller, *q*, (as shown in Fig. 5) and thence around the main or cloth guiding 15 roller *s*, and so on it continues its operation.

The roller *m* is provided with grooves whereas the roller *q* is smooth as against the contrary arrangement which is usual. Said roller *m* is fitted with adjusting screws *n*, 20 by means of which proper tension may be brought upon the several turns of the string *l*.

While I have shown my improvement applied to a ruling machine I do not wish to 25 be understood as limiting its scope merely to a machine of this type, for it may with slight modifications, be adapted to machines generally of this structure wherein belts or guiding cords are used for conveying, such 30 for instance as folding machines, the feed mechanism of printing presses etc.

I further do not wish to be understood

as limited to the structural details disclosed in the accompanying illustrations, but reserve the right to make such changes there-in as will better adapt the apparatus to its 35 purpose.

What I claim as new is,—

The combination with a ruling machine having a conveyer belt, of a guiding means 40 for the sheets carried by the belt, said guiding means comprising a single endless cord arranged in a plurality of convolutions adapted to lie in intimate contact with and travel in the direction of movement of the belt, grooved and smooth pulleys journaled within the machine and on which 45 said guiding means is arranged, said grooved pulley adapted to hold the several convolutions at proper relative position and to 50 guide the same, a pair of single pulleys disposed at either end of the grooved pulley and adapted to receive the cord from one end of a smooth pulley and direct said cord to the opposite end of the grooved pulley, and an adjusting device associated with one 55 of said pulleys whereby to uniformly tension the several convolutions of the cord.

In testimony whereof I affix my signature, in presence of two witnesses.

RICHARD A. MAGILL.
